UNITED STATES PATENT OFFICE.

ALVIN P. JOHNSON, OF SWAMPSCOTT, MASSACHUSETTS.

DESIGN FOR A CONFECTIONERY BOX.

Application filed May 21, 1924. Serial No. 9,676. Term of patent 14 years.

To all whom it may concern:

Be it known that I, ALVIN P. JOHNSON, a citizen of the United States, and a resident of Swampscott, in the county of Essex and State of Massachusetts, have invented a new, original, and ornamental Design for Confectionery Boxes, of which the following is a specification, reference being had to the accompanying drawing, forming a part thereof.

The figure is a perspective view of a confectionery box showing my new design, the essential feature of which is the outward resemblance to a frosted, edible cake.

I claim:

The ornamental design for a confectionery box as shown and described.

In testimony whereof, I have signed my name to this specification.

ALVIN P. JOHNSON.
